UNITED STATES PATENT OFFICE.

WILLIAM WALLACE BOYD, OF BUFFALO, NEW YORK, ASSIGNOR TO BUFFALO SCALE COMPANY, OF BUFFALO, NEW YORK, A CORPORATION OF NEW YORK.

SCALE.

1,325,188.

Specification of Letters Patent. Patented Dec. 16, 1919.

Application filed July 6, 1917. Serial No. 179,068.

To all whom it may concern:

Be it known that I, WILLIAM WALLACE BOYD, a citizen of the United States, residing at Buffalo, in the county of Erie and State of New York, have invented new and useful Improvements in Scales, of which the following is a specification.

This invention relates to scales and more particularly to the type which are used for weighing heavy objects like auto trucks, railroad cars and the like. One of the objects of this invention is to provide a coupling or connector between the pair of longitudinal levers generally known as "end levers" and the single transverse lever connecting with the steelyard generally known as a "cross lever", which coupling will permit of transmitting the movement from this pair of levers to the single lever with a minimum of friction and under a compression strain and with an action which is self alining, thereby not only increasing the strength and durability of the scale but also rendering the same more sensitive and accurate. A further object of this invention is to accomplish this purpose by means which are comparatively simple in construction, not liable to get out of order and capable of being produced at comparatively low cost.

In the accompanying drawings:

Figure 1 is a side elevation, partly in section, showing my improvements applied to a pair of longitudinal or end levers and a single cross lever of a scale. Fig. 2 is a fragmentary vertical transverse section of the same. Fig. 3 is a vertical longitudinal section taken on line 3—3, Fig. 2. Fig. 4 is a vertical transverse section taken on the correspondingly numbered line in Fig. 1. Fig. 5 is a perspective view of one of the sections of the strut or yoke forming part of the coupling which contains my invention. Fig. 6 is a similar view of one of the bearing blocks and associated parts embodying my improvements.

Similar characters of reference indicate corresponding parts throughout the several views.

1, 1. represent a pair of longitudinal levers of a scale which are arranged lengthwise in line and have their ends opposing each other. These levers are commonly known in the trade as "end levers" and are

operatively connected with the platform of the scale so that the free opposing ends of these levers are depressed when the load is placed upon the platform. 2 represents a single lever arranged transversely below the opposing ends of the end levers, this lever being commonly known in the trade as a "cross lever." The same is so mounted that it is depressed by the end levers and transmits motion to the scale beam by means of an upright steelyard in the usual and well known manner.

My invention resides in the means whereby the motion of the end levers is transmitted to the cross lever and in their preferred form these means are constructed as follows:

3 represents two nose pieces or irons one of which is arranged on the free end of each end lever so as to project laterally from opposite sides thereof. Each of these nose irons is preferably mounted on its respective lever by providing the upper part of the nose iron with an opening which receives the lever, and a set screw 4 arranged in a threaded opening in the nose iron and engaging with this lever. On each of these nose irons is mounted an upper knife edge 5 which is arranged horizontally and transversely thereto and has its opposite ends projecting from opposite sides of the respective nose iron. Each of these upper knife edges is preferably secured in its nose iron by casting the latter upon this knife edge so as to provide downwardly facing bearing surfaces on the underside of this knife edge at opposite ends thereof.

6, 6 represent two pairs of upper bearing blocks the members of each pair being arranged with their upper sides below the bearing faces at opposite ends of one of the upper knife edges and each of these blocks having a convex underside or bearing face 7 which is curved transversely or about an axis which is parallel with the length of the end levers. Each of these upper bearing blocks is provided with a concave upper surface which is preferably curved lengthwise or about an axis arranged transversely to the length of the end levers. In the central part of this bearing face the same is provided with a bearing piece 8 which is preferably constructed of hardened and ground steel preferably of substantially

2
dove-tail form and seated in a correspondingly shaped recess 9 formed transversely in this bearing block. The upper surface of this bearing piece is concave and preferably flush with the upper surface of this block and bears against the adjacent lower part of the adjacent upper knife edge. At its inner end each of these wearing pieces is preferably provided with a point or projection 10 which is adapted to engage the adjacent vertical surface of the respective nose piece or iron and thereby reduce to a minimum the friction between these parts if they should come into engagement with each other during the working of the scale.

On the cross lever is arranged a lower knife edge 11 which is preferably mounted thereon by casting this lever on the same, this being preferably effected by casting this lever on this knife edge, so that the latter is arranged transversely thereto or parallel with the end levers and so that the ends of this knife edge form two upwardly facing bearing surfaces on opposite sides of the cross lever.

12, 12 represent a pair of lower bearing blocks which are arranged on opposite sides of the cross lever and each provided on its underside with a curved face which is arranged above the upper side of one end of the lower knife edge and is curved about an axis which is transversely of the cross lever or parallel with the end levers. The upper end of each lower bearing block is provided with a convex bearing face which is curved about an axis arranged parallel with the cross lever or at right angles to the end levers. On the central part of the lower face of each lower bearing block the same is provided with a wearing piece 13 which is preferably constructed of hardened and ground steel and of dove-tail form and seated in a correspondingly shaped recess 14 formed in the lower face of this block and extending in a direction transversely of the cross lever or lengthwise of the end levers. The lower surface of each of the wearing pieces of each lower bearing block is preferably flush with the lower face of the respective block and at its inner end the same is provided with a point or projection 15 forming a friction which is adapted to engage with the adjacent vertical side of the cross lever and thereby reduce to a minimum the area of contact between these parts when they come into engagement with each other.

Between the upper and lower bearing blocks is arranged a strut or yoke which is adapted to transmit motion from the end levers to the cross lever by pressure. In the preferred form of this strut the same comprises two upright sections 16, 16 which are arranged transversely of the end levers and lengthwise of the cross lever on opposite sides of the latter. Each of these strut

sections or members is provided at its upper end on opposite sides of one of the end levers with two upwardly facing concave seats 17, 17 each of which is curved about an axis which is parallel with the end levers and engages with the lower convex face of one of the corresponding pair of upper bearing blocks. Centrally on its lower end each of the strut sections or members is provided with a downwardly facing lower concave bearing face 18 which is curved about an axis arranged transversely of the end levers and parallel with the cross lever and engages with the upper convex face of one of the lower bearing blocks. The two sections or members of the strut are preferably connected with each other by a tie so that they practically form one piece and move in unison. This connection may be effected in various ways, that shown in the drawings being suitable for this purpose and comprising an externally screw threaded tie rod 19 which is arranged horizontally and lengthwise of the end levers and passes through corresponding openings in the central parts of the strut sections and two pairs of clamping screw nuts 20, applied to this tie rod, the members of each pair bearing against opposite sides of one of the strut sections, as best shown in Fig. 3. By shifting these screw nuts on the tie rod the strut sections may be adjusted to bring their upper and lower bearing surfaces into the proper position relative to the bearing blocks with which they coöperate.

In order to hold each of the bearing blocks against displacement on its respective strut section the same is provided in the central part of its convex face with a retaining pin 21 which is secured at one end in a recess 22 in the respective bearing block while its opposite end projects beyond the convex face of the same and into a retaining recess 23 formed centrally in the corresponding concave bearing surface of the respective strut section.

When the end levers are depressed by a load imposed upon the platform of the scale this movement is transmitted by the upper and lower bearing blocks and the strut to the cross lever so that the latter turns about its axis at right angles to that of the end levers. During this movement the end levers rock upon the upper bearing blocks, the cross lever rocks upon the lower bearing blocks, and the upper bearing blocks rock on the upper ends of the strut in a direction transversely of the end levers and the lower bearing blocks rock on the lower ends of the strut in a direction lengthwise of the end levers in response to the pressure which is exerted upon these members. By this means the members which are subjected to compression strains while transmitting motion from the end levers to the cross lever auto-

15 matically align themselves into the proper position for enabling the upper and lower knife edges to engage fully with the respective bearing blocks at all times. The load which is imposed upon this coupling is therefore fully sustained while at the same time reducing to a minimum the friction between the several members which transmit the motion of the end levers to the cross lever, thereby obtaining the maximum sensitivity in the operation of the scale. It is therefore possible by the use of this coupling between the end levers and the cross lever to materially increase the accuracy of the scale without weakening the same or involving any material increase in cost of construction.

I claim as my invention:

1. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides of the respective longitudinal lever, two upper bearing blocks arranged on opposite sides of each longitudinal lever and each provided with an upper face engaging the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces which are arranged on opposite sides of the transverse lever and each of which is curved lengthwise, two lower bearing blocks arranged on opposite sides of said transverse lever and each having a convex upper face which is curved lengthwise and engages with one of the lower concave faces of the strut and each lower bearing block also having a lower face, and a lower longitudinal knife edge arranged on the transverse lever and having its ends arranged on opposite sides of the said lower lever and each of said ends engaging its upper side with the lower face of the adjacent lower bearing block.

2. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides

of the respective longitudinal lever, two upper bearing blocks arranged on opposite sides of each longitudinal lever and each provided with an upper face, the adjacent lower part of the upper knife edge having 70 a lower convex face which is curved transversely, an upright strut provided with two pairs of upper concave faces each of which is curved transversely and engages the convex face of one of said upper bearing blocks 75 and said strut being also provided with two lower concave faces which are arranged on opposite sides of the transverse lever and each of which is curved lengthwise, two lower bearing blocks arranged on opposite 80 sides of said transverse lever and each having a convex upper face which is curved lengthwise and engages with one of the lower concave faces of the strut and each lower bearing block also having a lower face 85 and a lower longitudinal knife edge arranged on the transverse lever and having its ends arranged on opposite sides of said transverse lever and each of said ends engaging its upper side with the lower face of 90 the adjacent lower bearing block, each of said bearing blocks being provided in its convex face with a retaining pin and the strut being provided in each of its concave faces with a recess which receives the retaining pin of the adjacent bearing block. 95

3. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge 100 projecting laterally from opposite sides of the respective longitudinal lever, two upper bearing blocks arranged on opposite sides of each longitudinal lever and each provided with an upper concave face opposite the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces which are arranged on opposite sides of the transverse lever and each of which 110 is curved lengthwise, two lower bearing blocks arranged on opposite sides of said transverse lever and each having a convex upper face which is curved lengthwise and engages with one of the lower concave faces 115 of the strut and each lower bearing block also having a lower concave face which is curved transversely, and a lower longitudinal knife edge arranged on the transverse lever and having its ends arranged on op- 120 125 130

- posite sides of said transverse lever and each of said ends engaging its upper side with the concave lower face of the adjacent lower bearing block, each of said bearing blocks being provided on its concave face with a wearing piece which engages with the adjacent part of the respective knife edge.
4. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides of the respective longitudinal lever, two upper bearing blocks arranged on opposite sides of each longitudinal lever and each provided with an upper concave face opposite the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces which are arranged on opposite sides of the transverse lever and each of which is curved lengthwise, two lower bearing blocks arranged on opposite sides of said transverse lever and each having a convex upper face which is curved lengthwise and engages with one of the lower concave faces of the strut and each lower bearing block also having a lower concave face, and a lower longitudinal knife edge arranged on the transverse lever and having its ends arranged on opposite sides of said transverse lever and each of said ends engaging its upper side with the concave lower face of the adjacent lower bearing block, each of said bearing blocks being provided on its concave face with a wearing piece which engages with the adjacent part of the respective knife edge and which is provided at its inner end with a friction point adapted to engage with the side of the adjacent member.
5. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides of the respective longitudinal lever, two pairs of upper bearing blocks arranged on opposite sides of each longitudinal lever and each provided with an upper concave seat engaging the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces which are arranged on opposite sides of the transverse lever and each of which is curved lengthwise and engages with one of the lower concave faces of the strut and each lower bearing block also having a lower concave face, and a lower longitudinal knife edge arranged on the transverse lever and having its ends arranged on opposite sides of said transverse lever and each of said ends engaging its upper side with the concave lower face of the adjacent lower bearing block, each of said bearing blocks being provided in its concave face with a dove-tail recess and a dove-tail wearing piece arranged in said recess and engaging with the adjacent part of the respective knife edge.
6. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides of the respective longitudinal lever, two upper bearing blocks arranged on opposite sides of each longitudinal lever and each provided with an upper concave opposite the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces which are arranged on opposite sides of the transverse lever and each of which is curved lengthwise, two lower bearing blocks arranged on opposite sides of said transverse lever and each having a convex upper face which is curved lengthwise and engages with one of the lower concave faces of the strut and each lower bearing block also having a lower concave face, and a lower longitudinal knife edge arranged on the transverse lever and having its ends arranged on opposite sides of said transverse lever and each of said ends engaging its upper side with the concave lower face of the adjacent lower bearing block, said strut comprising two sections each of which is provided with one

pair of said upper concave and one of said lower concave faces, and a tie connecting said sections.

7. In a scale, the combination of two longitudinal levers having their ends opposing each other, a transverse lever arranged below the ends of said longitudinal levers, and a coupling for connecting said longitudinal and transverse levers comprising nose irons arranged respectively on the ends of said longitudinal levers and each provided with an upper transverse knife edge projecting laterally from opposite sides of the respective longitudinal lever, two upper bearing blocks arranged on opposite sides of each longitudinal lever and each provided with an upper concave face engaging the adjacent lower part of the upper knife edge and having a lower convex face which is curved transversely, an upright strut provided with two pairs of upper concave faces each of which is curved transversely and engages the convex face of one of said upper bearing blocks and said strut being also provided with two lower concave faces

which are arranged on opposite sides of the transverse lever and each of which is curved lengthwise, two lower bearing blocks arranged on opposite sides of said transverse lever and each having a convex upper face which is curved lengthwise and engages with one of the lower concave faces of the strut and each lower bearing block also having a lower concave face and a lower longitudinal knife edge arranged on the transverse lever and having its ends arranged on opposite sides of said transverse lever and each of said ends engaging its upper side with the concave lower face of the adjacent lower bearing block, said strut comprising two sections each of which is provided with one pair of said upper concave and one of said lower concave faces, and a tie connecting said sections and comprising an externally threaded rod extending through openings in said strut sections, and screw nuts arranged on said rod and bearing against opposite sides of each of said strut sections.

WILLIAM WALLACE BOYD.
